UNITED STATES PATENT OFFICE.

THOMAS H. DAVIES, OF RUTHERFORD, NEW JERSEY.

MEANS FOR ATTACHING FLEXIBLE MATERIAL TO ROLLS OR DRUMS.

No. 886,582.

Specification of Letters Patent.

Patented May 5, 1908.

Application filed September 13, 1907. Serial No. 392,679.

To all whom it may concern:

Be it known that I, THOMAS H. DAVIES, a citizen of the United States, and resident of Rutherford, in the county of Bergen and State of New Jersey, have invented certain new and useful Improvements in Means for Attaching Flexible Material to Rolls or Drums, of which the following is a specification.

10 In some typewriting machines it is customary to attach a strip of cloth to the inking ribbon, roll or drum, and to attach the inking ribbon to such strip by means of a pin, whereby the operator's fingers become soiled 15 in attaching and detaching the inking ribbon, and the pin is more or less objectionable when the ribbon is being used, and in other rolls and drums on which flexible strips, ribbons or the like are wound it is customary to attach them to the roll or drum by tacks and 20 in other ways.

The object of my invention is to provide improved means for detachably connecting flexible material, such as ribbons, strips, and 25 the like, to rolls or drums without the use of pins or tacks; and whereby the ribbon can be readily attached and detached without unduly handling the same, to the end that the fingers of the operator may be kept clean.

30 In carrying out my invention I provide a roll or drum with a gripper extending along the same and movably supported to enable it to be swung outwardly to permit the insertion and removal of a ribbon or flexible strip 35 and to be pressed down into contact with the latter for holding the same upon the roll or drum. In the example illustrated I provide a roll or drum with a groove or recess in its surface, a gripper to enter said groove, arms 40 pivotally supported adjacent the roll and carrying said gripper, and means for holding said gripper in closed position, whereby the gripper will engage the ribbon or flexible strip and hold the same in the groove, and 45 whereby the gripper may lie substantially flush with or within the periphery of the roll or drum to permit proper winding of the ribbon or strip thereon.

The invention also comprises the novel 50 tails of improvement and combinations of parts that will be more fully hereinafter set forth and then pointed out in the claims.

Reference is to be had to the accompanying drawings forming part hereof, wherein, 55 Figure 1 is a face view of a roll or drum

provided with my improvements, showing the ribbon partly wound thereon, Fig. 2 is an end view thereof, Fig. 3 is a cross section, Fig. 4 is a central section, substantially on the line 4, 4, in Fig. 2, Fig. 5 is a cross section substantially on the line 5, 5, in Fig. 1, and Fig. 6 is a detail of the gripper.

Similar numerals of reference indicate corresponding parts in the several views.

The numeral 1 indicates a suitable shaft 65 upon which is secured a roll or drum 2 of suitable material, such as wood, and at 3 are flanges or disks secured at the ends of the roll or drum, as by nails 4. The roll or drum is provided with a groove or recess 5 at its 70 periphery into which a gripper 6 is adapted to pass to hold therein the end of ribbon, tape or other flexible strip 7. Said gripper is shown mounted upon a shaft 8 which extends parallel with groove 5 and passes 75 through suitable curved slots 9 in the disks or plates 3, and at 10 are arms shown on the exterior of disks 3 and pivotally supported thereon by screws or studs 11, whereby said arms may swing to carry shaft 8 through the 80 slots 9 toward and from groove 5 for carrying the gripper toward and from the latter. Shaft 8 may have finger pieces 8^a at its ends for convenience in swinging the gripper back and forth. The arms 10 are shown provided 85 with angularly disposed end portions at 10^a against which springs 12 bear for holding said arms in set position, which springs are secured to disk 3 by screws 13 or in any suitable manner, said springs being shown located between studs 14 on disks 3 to hold the springs in operative position. The gripper 6 is shown provided with teeth or projections 6^a to engage the ribbon or the like 7 when in groove 5, and said gripper is shown composed 90 of a piece of sheet metal suitably bent to form the bearing 6^b for shaft 8 and the extension 6^c that is adapted to lie upon the roll or drum 2, and the part 6^c may enter the recess 2^a in the surface of roll 2 so as to be substantially flush with the periphery of the roll 95 and cover the end of the ribbon, and also to extend over groove 5 so that the ribbon or strip will wind smoothly around the roll.

In using my improvements the gripper is 105 swung outwardly to carry it away from groove 5, then the end of the ribbon or flexible strip 7 is laid in or over groove 5, the gripper is swung down to enter said groove, and its teeth 6^a engage the ribbon and hold 110

it in the groove, as shown in Fig. 5, so that the ribbon may be wound closely about the roll. To release the ribbon it is merely necessary to swing the gripper outwardly when it will be free from the ribbon.

By means of my improvements the ribbon may be directly and readily connected with the roll without requiring the use of pins to attach the ribbon to a strip secured to the roll, and without tacking the ribbon to the roll, and thereby the ribbon is readily detachable from the roll, and the fingers of the operator are not liable to be soiled when applying an inking ribbon to or removing it from the roll.

While I have referred to my improvements as being particularly adapted for use in attaching typewriter inking ribbons to rolls, it will be understood that my improvements may be used for various purposes whereby flexible strips or sheets are to be connected with a roll or drum to be wound thereon, and the arms 10 may be supported upon the roll in any suitable manner.

Having now described my invention what I claim is;

1. The combination of a roll provided with a groove, with a gripper movably connected with the roll and adapted to enter said groove, and a spring acting on the gripper for holding said gripper in the groove and for holding said gripper out of the groove.

2. The combination of a roll, with a gripper provided with teeth, arms movably supporting said gripper, and a spring for holding said gripper against the roll and away from the roll.

3. The combination of a roll provided with a groove, and plates at the ends of said roll having slots, with a shaft passing through said slots and provided with a gripper, means for movably supporting said shaft

and a spring to hold said gripper in the groove and out of the groove.

4. The combination of a roll provided with a groove and plates at the ends of said roll having slots, with a shaft passing through said slots and provided with a gripper, arms supporting said shaft and pivotally connected with the roll, and a spring acting on said arms for holding said shaft against the roll.

5. The combination of a roll having a groove, with a gripper having teeth to enter the groove and an extension to lie over the roll, arms movably supporting the gripper, and a spring for holding the gripper in the groove and out of the groove.

6. The combination of a roll provided with a groove and plates at the ends of the roll provided with slots, with a shaft entering said slots, a gripper mounted upon said shaft and provided with teeth to enter said groove and having an extension to overlie the roll, arms movably supporting said roll and means to hold said gripper in the groove.

7. The combination of a roll provided with a groove and plates at the ends of the roll provided with slots, with a shaft entering said slots, a gripper mounted upon said shaft and provided with teeth to enter the groove and having an extension to overlie the roll, arms movably supporting said roll, and a spring supported by one of said plates and co-acting with one of said arms to hold the gripper in the groove.

Signed at New York city, in the county of New York, and State of New York, this 12th day of September, A. D. 1907.

THOMAS H. DAVIES.
